UNITED STATES PATENT OFFICE.

THEODOR QVILLER, OF LILLESTROMMEN, NEAR CHRISTIANIA, NORWAY.

SAND AND SPLINT CATCHER FOR WOOD-PULP PLANTS AND THE LIKE.

1,306,436.

Specification of Letters Patent. Patented June 10, 1919.

Application filed October 31, 1918. Serial No. 280,519.

To all whom it may concern:

Be it known that I, THEODOR QVILLER, a subject of the King of Norway, of Lillestrommen, near Christiania, Norway, have 5 invented certain new and useful Improvements in Sand and Splint Catchers for Wood-Pulp Plants and the like; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part of 15 this specification.

The present invention has for its object to provide an automatical sand and splint catcher for wood pulp plants and the like.

The known sand catchers usually comprise 20 long and comparatively shallow channels with transverse grooves or baffles extending across the whole breadth of the catcher from the bottom of the same up to somewhere below the level of the pulp. The purpose of 25 said cross ribs or baffles is to make splints and other particles, which are heavier than the good fibers, sink and settle in the spaces between the ribs. If the pulp comprises a 30 large amount of splints and unboiled parts the spaces between the ribs are soon filled, whereupon impurities, splints, etc., follow the pulp current, and the effect of the catcher is automatically stopped.

For this reason sand catchers of this type 35 very often have to be put out of action in order to be cleaned which gives a lot of work and at the same time makes it necessary to use a double set of catchers in order to keep the plant working continually during the 40 cleaning process.

It is obvious that catchers of this kind take up a large floor space and so necessitate extensive buildings.

The improved sand catcher according to 45 the present invention is intended to avoid the above mentioned disadvantages being adapted to automatically remove the impurities settling in the same, so that it may be kept in continued operation making the use of 50 reserve catchers unnecessary.

On the drawing—

Figure 1 is a plan view of the sand catcher.

Fig. 2 is a vertical section through the same and

Fig. 3 is a vertical section on the line 55 III—III of Fig. 2 seen in the direction of the arrows.

The sand catcher itself comprises a large flat bottomed cylindrical vessel A into which the pulp is conducted tangentially through 60 channel C. A wall B extending downwardly to some distance above the floor of vessel A serves to guide the pulp current along the cylindrical wall of vessel A until it is conducted into the form of a spiral toward the 65 center of vessel A where a rotating sieve drum D is mounted. The pulp fibers together with the water in which they are swimming will pass through the perforated sieve drum D and out through one end of the 70 sieve drum into channel E, which serves to conduct the pulp to the sorting machine.

As it will be seen on the drawing the end of the sieve drum which serves as outlet for the pulp is provided with a collar or flange 75 projecting against a corresponding collar or flange F mounted on the outlet channel E.

During its passage in the flat bottomed vessel A from channel C to sieve drum D the pulp will be sorted as the heavier parts settle 80 on the bottom of the vessel. Scrapers G mounted on rotating arms H carry the impurities with them along the bottom of the vessel dropping them finally into the radial channel I in the bottom of the vessel said 85 channel I being provided with a conveyer screw J. It is an important point that the scrapers G rotate with a velocity corresponding exactly to the movement of the pulp so that no turbulent currents are created. 90

The coarser particles which follow the pulp current to the sorting drum D without passing through the same will also gradually settle on the bottom of the vessel and be carried by scrapers G to the channel I with the 95 conveyer screw J. Said conveyer screw conducts the impurities to a bucket conveyer K or the like carrying the impurities into the elevated channel L, from which they are conducted through fall tube M into a smaller 100 settling tank N on the bottom of which the coarser and heavier particles come to rest, while all the finer fibers carried with the impurities are separated from the latter by means of a slow current of water going in an 105 upward direction through settling tank L and flowing together with the fine fibers over the edge of said settling tank into an annular

channel P from which they are conducted through an inclined channel Q back to the catcher vessel A.

The impurities settling in tank L at suitable intervals are removed by means of valve R. Said valve R may also be provided with an automatical controlling mechanism for opening and closing the same at certain intervals.

10 Claims:

1. A sand or splint catcher for wood pulp plants and the like, comprising a cylindrical flat bottomed vessel, means for conducting the pulp tangentially into said vessel thereby moving the pulp current along the cylindrical wall of the vessel, a radial channel in the bottom of said vessel, means for conveying impurities settling on the bottom of the vessel into said radial channel, and means in said radial channel for conveying said impurities out of the vessel.
- 15 2. A sand or splint catcher for wood pulp plants and the like, comprising a cylindrical flat bottomed vessel, means for conducting the pulp tangentially into said vessel, a spiral partition in the latter extending down to some distance above the bottom of the same for guiding the pulp current along the cylindrical wall of the vessel, a radial
- 20 30 channel on the bottom of said vessel, means for conveying impurities settling on the bottom of the vessel into said radial channel, and means in said radial channel for conveying said impurities out of the vessel.
- 25 35 40 45 3. A sand or splint catcher for wood pulp plants and the like, comprising a cylindrical flat bottomed vessel, means for conducting the pulp tangentially into said vessel thereby moving the pulp current along the cylindrical wall of the vessel, a radial channel in the bottom of said vessel, a rotating spider provided with scrapers near the bottom of the vessel for conveying impurities settling on the bottom of the vessel into said radial channel, and means in said radial channel for conveying said impurities out of the vessel.
- 40 45 50 55 60 65 70 75 80 85 90 95 4. A sand or splint catcher for wood pulp plants and the like, comprising a cylindrical

flat bottomed vessel, means for conducting the pulp tangentially into said vessel, a spiral partition in said vessel extending down to some distance above the bottom of the same for guiding and moving the pulp current along the cylindrical wall of the vessel, a radial channel in the bottom of said vessel, and a rotating spider provided with scrapers below said spiral partition for conveying impurities settling on the bottom of the vessel into said radial channel, and means in said radial channel for conveying said impurities out of the vessel.

5. A sand or splint catcher for wood pulp plants and the like, comprising a cylindrical flat bottomed vessel, means for conducting the pulp tangentially into said vessel and moving the pulp current along the cylindrical wall of the vessel, a radial channel in the bottom of said vessel, means for conveying impurities settling on the bottom of the vessel into said radial channel, an auxiliary settling tank, means for conveying the particles settling in said radial channel into said settling tank, and means for conducting the finer particles carried with the impurities back from said settling tank into the catcher.

6. A sand or splint catcher for wood pulp plants and the like, comprising a cylindrical flat bottomed vessel, means for conducting the pulp tangentially into said vessel, a spiral partition in said vessel extending down to some distance above the bottom of the same for guiding the pulp current along the cylindrical wall of said vessel, a rotating sieve drum inclosed by said spiral wall for sorting out the fine particles, means for conveying impurities settling on the bottom of the vessel into said radial channel, and means in said radial channel for conveying said impurities out of the vessel.

In testimony that I claim the foregoing as my invention, I have signed my name in presence of two subscribing witnesses.

THEODOR QVILLER.
